UNITED STATES PATENT OFFICE.

JOSEPH BERGER, OF UTICA, NEW YORK, ASSIGNOR TO UNION SPECIAL MACHINE COMPANY, OF CHICAGO, ILLINOIS, A CORPORATION OF ILLINOIS.

PRESSER FOOT FOR SEWING MACHINES.

Application filed September 1, 1921. Serial No. 497,533.

To all whom it may concern:

Be it known that I, JOSEPH BERGER, a citizen of the United States, residing at Utica, in the county of Oneida, State of New York, have invented certain new and useful Improvements in Presser Feet for Sewing Machines, of which the following is a description, reference being had to the accompanying drawing, and to the figures of reference marked thereon.

The invention relates to new and useful improvements in a presser foot for a sewing machine, and more particularly to a presser foot which is adapted to be used in connection with a cover seaming mechanism.

An object of the invention is to provide a presser foot having a shiftable auxiliary section in rear of the stitching mechanism with means for positively shifting said section so that the space or recess receiving the seam portion of the fabric sections may be adjusted to accommodate different thicknesses of seams.

A further object of the invention is to provide a presser foot of the above character with means for rigidly locking the auxiliary section in any position to which it may be shifted.

These and other objects will in part be obvious and will in part be hereinafter more fully disclosed.

In the drawings which show by way of illustration one embodiment of the invention:

Figure 1 is a view partly in side elevation and partly in vertical section showing a portion of a sewing machine and the improved presser foot applied thereto;

Fig. 2 is a top plan view of the presser foot, and showing in broken lines one of the trimming members;

Fig. 3 is a bottom plan view of the presser foot;

Fig. 4 is a sectional view on the line 4—4 of Fig. 2;

Fig. 5 is a perspective view of the auxiliary section removed from the presser foot, and

Fig. 6 is a view similar to Fig. 4, but showing only a portion of the foot and the parts adjusted to accommodate the covered seam.

The invention in its broadest aspects consists of a presser foot having a supporting shank on which is rigidly mounted the main

section of the presser foot. Associated with this main section is an auxiliary section which is located in rear of the stitching mechanism and which is capable of being shifted vertically relative to the main section of the presser foot in order to bring it to a position flush with the main section of the presser foot or slightly raised thereabove to provide a space or recess through which the seam passes after it is completed. Means is provided for positively shifting this auxiliary section, and means is also provided for positively locking the auxiliary section in any position to which it is shifted. From certain aspects of the invention, the presser foot also includes a yielding auxiliary section located on the opposite side of the shiftable auxiliary section from the main portion of the presser foot.

Referring more in detail to the drawings, the presser foot is shown as applied to a sewing machine of the feed-off-the-arm type. A work supporting arm is indicated at 1, the needle bar at 2, and said needle bar is provided with a plurality of needles 3, preferably three in number. Cooperating with the needles within the work supporting arm is a looper 4 carried by a looper shaft 5. This looper is of the thread carrying type. The material is fed off from the end of the work support by a feeding mechanism which includes a main feed dog 6 and an auxiliary feed dog 7. The machine of the type referred to is fully shown and described in the patent granted to Joseph Berger, October 19, 1920, Number 1,356,334, and further description thereof is not thought necessary.

The presser foot consists of a supporting shank 8 which is secured to a presser bar 9 of the usual construction. This shank 8 carries a main foot section 10 which is rigidly supported by the shank. Said main foot section and shank is provided with a vertically extending portion 11 (see Fig. 4) having an overhanging lateral projection 12. Located alongside of the main foot section is an auxiliary foot section 13 which is provided with an upstanding shank 14 having a laterally projecting plate 15 perforated at 16, and also a laterally projecting plate 17 cut away at 18. The main foot section 10 is cut away as indicated at 19 in Fig. 4 to receive this auxiliary foot section 13. The thickness of the auxiliary foot section is less than the cut away portion so that said auxil-

ary foot section may be adjusted so as to form a recess or space which is adapted to receive the seam. In Fig. 6 of the drawings, I have shown diagrammatically two overlapped fabric sections F—F which are connected by a covered seam indicated at f. The auxiliary foot section 13 is raised relative to the main section 10 so that the under surface of the auxiliary section 13 is above the under surface of the main section 10 and this forms a recess or space through which the covered seam f passes. Alongside of the auxiliary section 13 is a yielding section 20.

The auxiliary section 13 is raised and lowered by means of a screw 21. This screw has a relatively large flat head which lies between the plates 15 and 17. Said head overlies the side walls of the slot 18 in the plate 17 and access is obtained to the slot in the head of the screw through the opening 16. This head substantially fits the space between the plates and therefore the screw can be readily turned, but any endwise movement of the screw will raise or lower the auxiliary section 13, depending upon which way the screw is turned. The screw is threaded into the overhanging portion 12 of the main section of the presser foot. The shank 14 of the auxiliary section 13 is provided with a slot 22. The screw 23 passes through the slot and is threaded into the vertical portion 11 of the presser foot. The auxiliary section 20 is also provided with a slot 24 through which the screw passes, and said screw has a shoulder 25 which overlies the side walls of the slot 22, so that when the screw is turned in, the auxiliary section 13 may be firmly clamped. The auxiliary section 20 slides freely up and down in a guiding recess therefor, and is held in place by a cover plate 26. A spring 27 bearing on the upper end of the auxiliary section yieldingly forces the same downwardly, and the screw 23 serves to limit the downward movement of this yielding section. The slot 24, however, permits the yielding section to move upwardly so as to bring the under face of the yielding section in alinement with the main section 10 of the foot. There is sufficient distance between the head of the screw 23 and the shoulder 25 so that when the auxiliary section 13 is rigidly clamped, the yielding section is free to move up and down.

The auxiliary section 13 is located in rear of the stitching mechanism and is provided with a cut away portion 28 which preferably tapers from its top rearwardly to the lower face thereof. Stitch fingers 29 and 30 are provided which project rearwardly into said cut away portion 28. The presser foot is provided with a guiding slot 31 which is so shaped as to receive the upturned edges of two fabric sections and direct the same to a trimming mechanism, after which said upturned sections are returned to overlapped

relation and stitched by a covering stitching mechanism. This forms a covered seam of some thickness and the purpose of shifting the auxiliary section 13 is to position the same so that it will bear firmly on the top 70 of the covered seam, but without raising the main section of the foot from firm contact with the section of the fabric underneath the same. Thus it is that the presser foot will hold the fabric sections at both sides of 75 the seam and in the region of the seam in firm contact with the feed dogs of the feeding mechanism so as to insure a uniform feeding of the fabric sections. It is to be understood that this section 13 plays no part 80 in the chaining off between articles as the stitch fingers perform this function in a manner well known in the art. If the thickness of the seam varies, on different characters of material, or with different threads, 85 the section 13 may be positively shifted by loosening the screw 23 and turning the screw 21. After it has been shifted to proper position, then the screw 23 is turned in to lock it in this position. The section 13 90 therefore is always under the control of the screw 21 and is held thereby in any position to which it may be shifted, and the screw 23 is an additional locking means to hold the section rigidly locked in its adjusted position.

While I have described my presser foot as particularly adapted for use in the forming of a covered seam having overlapped fabric sections, it will be understood of course, that it may be used in connection with covered seams of any character, whether the edges are overlapped or not, and by the shifting of the auxiliary section, sufficient space is provided to accommodate the threads uniting the fabric sections.

It is obvious that minor changes in the details of construction and the arrangement of the parts may be made without departing from the spirit of the invention as set 105 forth in the appended claims.

Having thus described the invention, what I claim as new and desire to secure by Letters Patent, is:—

1. A presser foot for sewing machines including a supporting shank, a main foot section rigidly carried thereby, an auxiliary foot section, and means for positively shifting said auxiliary section vertically up and down relative to the main foot section to 115 various set positions.

2. A presser foot for sewing machines including a supporting shank, a main foot section rigidly carried thereby, an auxiliary foot section, means for positively shifting said auxiliary section to various set positions vertically relative to the main foot section, and means for positively locking the auxiliary foot section in its adjusted positions.

3. A presser foot for sewing machines including a supporting shank, a main foot section rigidly carried by said supporting shank, an auxiliary section at one side of the main foot section and in rear of the stitching mechanism, means for shifting said auxiliary section vertically relative to the main foot section, and means for locking said auxiliary section in its adjusted positions. 70
- 10 4. A presser foot for sewing machines including a supporting shank, a main foot section rigidly carried by said supporting shank, an auxiliary section at one side of the main foot section and in rear of the stitching mechanism, means for shifting said auxiliary section vertically relative to the main foot section, means for locking said auxiliary section in its adjusted positions, and a yielding section alongside of said first-named auxiliary section. 75
- 15 5. A presser foot for sewing machines including a supporting shank, a main section rigidly carried thereby, a yielding auxiliary section spaced from the main section, a shiftable auxiliary section located between the yielding section and the main section of the presser foot, and means for shifting said intermediate section vertically relative to the main foot section to various set positions, 80 said intermediate section being located in rear of the stitching mechanism. 85
- 20 6. A presser foot for sewing machines including a supporting shank, a main section rigidly carried thereby, a yielding auxiliary section spaced from the main section, a shiftable auxiliary section located between the yielding section and the main section of the presser foot, means for shifting said intermediate section vertically relative to the main foot section, said intermediate section being located in rear of the stitching mechanism, and independent means for locking said intermediate section in its adjusted positions. 90
- 25 7. A presser foot for sewing machines including a supporting shank, a main foot section carried thereby, said main foot section having a cut away portion, a vertical portion, and an overhanging member, an auxiliary section located in the cut away portion and having a shank extending alongside of said vertical portion, and projecting plates extending over said overhanging portion, said projecting plates being spaced, and a screw threaded into said overhanging portion and having a relatively flat head fitting between the spaced plates for shifting said auxiliary section vertically relative to the main section, the shank of the auxiliary section having a slot formed therein, and a screw passing through said slot 95 threaded into a vertical portion of the main section, said screw having a shoulder adapted to engage the shank for locking the auxiliary section in adjusted positions. 100
- 30 8. A presser foot for sewing machines including a supporting shank, a main foot section carried thereby, said main foot section having a cut away portion, a vertical portion, and an overhanging member, an auxiliary section located in the cut away portion and having a shank extending alongside of said vertical portion, and projecting plates extending over said overhanging portion, said projecting plates being spaced, and a screw threaded into said overhanging portion and having a relatively flat head fitting between the spaced plates for shifting said auxiliary section vertically relative to the main section, the shank of the auxiliary section having a slot formed 105 therein, and a screw passing through said slot threaded into a vertical portion of the main section, said screw having a shoulder adapted to engage the shank for locking the auxiliary section in adjusted position. 110
- 35 9. A presser foot for sewing machines including a supporting shank, a main foot section carried thereby, said main foot section having a cut away portion, a vertical portion, and an overhanging member, an auxiliary section located in the cut away portion and having a shank extending alongside of said vertical portion, and projecting plates extending over said overhanging portion, said projecting plates being spaced, and a screw threaded into said overhanging portion and having a relatively flat head fitting between the spaced plates for shifting said auxiliary section vertically relative to the main section, the shank of the auxiliary section having a slot formed 115 therein, and a screw passing through said slot threaded into a vertical portion of the main section, said screw having a shoulder adapted to engage the shank for locking the auxiliary section in adjusted position. 120
- 40 10. A presser foot for sewing machines including a supporting shank, a main foot section carried thereby, said main foot section having a cut away portion, a vertical portion, and an overhanging member, an auxiliary section located in the cut away portion and having a shank extending alongside of said vertical portion, and projecting plates extending over said overhanging portion, said projecting plates being spaced, and a screw threaded into said overhanging portion and having a relatively flat head fitting between the spaced plates for shifting said auxiliary section vertically relative to the main section, the shank of the auxiliary section having a slot formed 125 therein, and a screw passing through said slot threaded into a vertical portion of the main section, said screw having a shoulder adapted to engage the shank for locking the auxiliary section in adjusted position. 130
- 45 11. A presser foot for sewing machines including a supporting shank, a main foot section carried thereby, said main foot section having a cut away portion, a vertical portion, and an overhanging member, an auxiliary section located in the cut away portion and having a shank extending alongside of the shank of the shiftable auxiliary section, and a spring for normally forcing said yielding auxiliary section downwardly, said yielding auxiliary section having a slot through which the clamping screw passes, said screw operating to limit the downward movement of the yielding auxiliary section. 135

including a supporting shank, a main foot section rigidly carried thereby, a yielding foot section spaced from the main foot section, stitch fingers carried by the main section, an auxiliary section located between the yielding section and the main section, and in rear of the stitch fingers, said auxiliary section having a cut away portion

into which said stitch fingers project, and means for positively raising and lowering ¹⁰ said intermediate auxiliary section relative to the main foot section.

In testimony whereof, I affix my signature.

JOSEPH BERGER.
